UNITED STATES PATENT OFFICE.

LUCIAN BLACKARD, OF HAYTI, MISSOURI.

BROOM.

1,157,074.

Specification of Letters Patent.

Patented Oct. 19, 1915.

Application filed March 24, 1915. Serial No. 16,781.

To all whom it may concern:

Be it known that I, LUCIAN BLACKARD, a citizen of the United States, residing at Hayti, in the county of Pemiscot and State of Missouri, have invented certain new and useful Improvements in Brooms, of which the following is a specification, reference being had to the accompanying drawings.

The present invention relates broadly to new and useful improvements in brooms and has particular reference to an improved form of fastening means whereby the broom corn is secured to the handle.

The principal object of the invention is to provide a fastening means which is relatively simple in construction and may therefore be cheaply manufactured.

A further object is to provide a pair of coacting securing plates which are adapted to be disposed against opposite faces of the head portion of the broom and are accompanied by fastening means whereby they may be drawn into severe clamping engagement against the broom straws for holding the same in a compact bundle.

The above and other incidental objects of a similar nature which will be hereinafter more specifically treated are accomplished by such means as are illustrated in the accompanying drawings, described in the following specifications and then more particularly pointed out in the claims which are appended hereto and form a part of this application.

With reference to the drawing wherein there has been illustrated a further embodiment of the invention as it is reduced to practice and throughout the several views of which similar reference numerals designate corresponding parts, Figure 1 is a face view of the broom with the parts thereof in complete assembled relation. Fig. 2 is a section taken longitudinally and medially through the broom in a plane at right angles to the head plates. Fig. 3 is a face view of the broom showing the same before the head plates are applied; Fig. 4 is a side elevation showing the handle and one bundle of material secured thereto; Fig. 5 is a transverse section taken through the broom at the point whereat the wire receiving plates are attached; Fig. 6 is a detail face view of one of the head plates; Fig. 7 is an edge view of the plate shown in Fig. 6; Fig. 8 is a detail view showing the manner in which the wire is passed through the wire receiving plate; Fig. 9 is a detail view showing particularly the tube and screw employed in holding the head plates in position against the brush forming bundles of corn; and Fig. 10 is a view showing the broom in a partially completed state with the bundles of corn inverted on the handle.

As best disclosed in Fig. 3 of the accompanying drawings, the broom is constituted of two separate bundles of corn 10 and 11 which are secured to a handle 12. The bundles 10 and 11 are equal as to size and the corn of each is held together in compact relation prior to the securing of the bundles to the handle by binding wires 13. Prior to the application of the bundles 10 and 11 to the handle there is secured to the terminal of this latter member and at diametrically opposite points thereof a pair of wire receiving plates 15 and 16. These members 15 and 16 are in length approximately equal to the thickness of the broom handle and are secured in flat wall recesses 17 by means of an elongated rivet 18 which passes through the handle and plates. Each terminal of each of the members 15 and 16 is apertured so that a wire indicated at 19 may be passed through each pair of adjacent terminals of the plates and passed about the two bundles 10 and 11 as shown best in Fig. 5. The terminals of the wire are twisted about each other, as shown in Fig. 5, at 19'. The intermediate portions of the wire are seated in grooves formed in the handle at diametrically opposite points. After the wire 19 has been thus applied with the bundles inverted on the handle, the bundles are rotated in opposite directions in planes parallel to the handle and about the wire 19 as an axis. The slack in the wire 19 is thus taken by twisting, as shown best in Figs. 5 and 8. The binding wire 14 is then applied. After the bundles have been thus secured, the head plates 20 and 21 are applied to opposite sides of the head portion constituted by the attached terminal portions of the straw bundles 10 and 11. These head plates 20 and 21 are substantially similar, each being formed

from a single blank of sheet metal, which is cut to form an elongated body portion 22 and the pairs of laterally extending arms 23, 24 and 25. These members 23, 24 and 25 of each of the plates are adapted to engage against the head portion of the bundles, as shown in Fig. 1. The body portion of each plate is adapted to cover and conceal the space between the terminals of the bundles 10 and 11. As a means for drawing the two plates into clamping engagement against the bundles, I provide the one plate 20 with a plurality of internally threaded tubes or sleeves 26. Into these tubes are threaded screws 27 which are passed through the apertures 28 of the plate 21. It will be readily appreciated that the screws may be threaded home to draw the two plates into the desired clamping engagement against the straw. One 20 or more of the sleeve members 26 may be passed through the handle for holding the plate against movement.

In reduction to practice, it has been found that the form of this invention illustrated 25 in the drawings, and referred to in the above description as the preferred embodiment, is the most efficient and practical; yet realizing that the conditions concurrent with the adoption of this device will necessarily vary, 30 it is desirable to emphasize the fact that various minor changes in details of construction, proportion and arrangement of parts may be resorted to, when required, without sacrificing any of the advantages 35 of this invention, as defined by the appended claims.

I desire to direct particular attention to the fact that the wire receiving plates 15 and 16, the head plates 20 and 21 and the handle 40 12 may be employed in constructing a new broom, after the corn initially used, has been worn out. The only parts which must be replaced, when a new broom is to be made, are the corn and the binding wire.

45 What is claimed is:—

1. A broom including a handle, a pair of wire receiving plates secured to the handle at diametrically opposite points thereof, independent bundles of material constituting 50 the brush portion of the broom, said bundles being disposed against the outer faces of the plates and a wire passing through the plates and about the bundles for securing the same against the plates.

55 2. A broom including a handle, a pair of wire receiving plates secured to the handle at diametrically opposite points thereof, two independent bundles of material constituting the brush portion of the broom, a wire 60 passing through the plates and about the bundles for securing the same against the plates, and a pair of head plates detachably secured to the handle, said head plates being disposed to bear against opposite faces of 65 the head of the brush portion to close the

space between the upper ends of the two bundles.

3. A broom including a handle, a pair of wire receiving plates detachably secured thereto at diametrically opposite points, said plates being arranged in parallel relation to each other and being each provided with terminal apertures, separate bundles of material constituting the brush portion of the broom, there being a bundle disposed against each plate, a wire passing through the apertures of the plate and about the bundles for securing the same against the plates and handle, and a pair of head plates detachably secured to the handle and positioned to bear against the bundles on opposite sides thereof, said head plates being also disposed to conceal the space between those terminals of the bundles which are attached to the handle. 70 75 80

4. A broom including a handle, wire receiving plates detachably secured thereto at diametrically opposite points and in parallel relation to each other, separate bundles of brush forming material, a wire passing through the plates and about the bundles 90 for securing the same to the handle and plates, and a pair of head plates detachably secured to the handle, said head plates being disposed in parallel spaced relation to each other and at right angles to the wire receiving plates, each of said head plates including a rectangular body portion, and a plurality of laterally extending fingers, said body portion being adapted to bear against the handle, and said finger members being adapted 95 100 105 to engage against the bundles of material.

5. A broom including a handle, parallel wire receiving plates secured thereto, bundles of brush forming material disposed against the wire receiving plates, a wire passing through the plates and about the bundles, and a pair of head plates detachably secured to the handle on opposite sides of the broom, said plates being disposed at right angles to the wire receiving plates. 110

6. A broom including a handle, separate bundles of brush forming material secured thereto, there being a space between the bundles at the attached terminals of these members, and a pair of removable head plates disposed against opposite sides of the broom head for entirely closing said space. 115

7. A broom including a handle, independent bundles of material constituting the brush portion of the broom, and a wire passing around the bundles and handle, for securing the bundles thereto, said wire being twisted on each side of the handle to define a central band which surrounds and clamps the handle, and terminal bands which surround and clamp the bundles to the handle. 120 125

8. A method of making brooms which consists in applying independent bundles of material to a handle on opposite sides there- 130

of, passing a wire about the bundles and handle and then rotating the bundles in planes parallel to the handle to twist the wire on each side thereof, whereby the slack in the wire is taken up, the wire clamped about the handle, and the bundles compressed and clamped against the handle.

In testimony whereof I hereunto affix my signature in the presence of two witnesses.
